UNITED STATES PATENT OFFICE

WILLIAM M. TRAFTON, OF PROVIDENCE, RHODE ISLAND, AND JOSEPH ARMSTRONG, OF ALLSTON, MASSACHUSETTS, ASSIGNORS TO AMERICAN MOISTENING COMPANY, OF BOSTON, MASSACHUSETTS, A CORPORATION OF MAINE

HUMIDIFIER

Application filed October 1, 1926. Serial No. 138,959.

This invention relates to improvements in humidifiers. More particularly it relates to an attachment for humidifiers of the vertical forced draft type, whereby escape of too 5 large particles of moisture into the room is more securely prevented.

Humidifiers of this type have a nozzle arranged centrally of the casing, near its top, to direct the jet of water spray conically 10 downward and outward against the inside wall of the casing. An air blast driven down through this spray by a rotary fan located above it entrains fine particles of moisture and carries them into the room atmosphere. 15 It is important that the particles thus carried be small enough to float in the air until evaporated, for in some instances, as where delicate fabrics are in process of manufacture, the falling of a single drop of water in the 20 room may cause considerable damage. The avoidance of this evil has been the subject of much consideration by inventors, yet modern apparatus sometimes is faulty in this respect.

The present invention eliminates this 25 prevalent danger in forced draft humidifiers by intercepting such parts of the water jet as might furnish such large drops, at all times of diminished water pressure, and guiding the intercepted water to the drain through a 30 course protected from the fast moving air current. Another feature is that whatever part of the air blast is near the axis of the casing is by the device of the invention either directed outward into the faster moving currents or 35 entrapped and guided with the intercepted water to the base of the casing. It is moreover an important detail that the device of the invention is simple, inexpensive and may be readily installed in humidifiers as at present 40 commonly constructed.

These ends are gained with a water intercepting and air deflecting device in the nature of a covered funnel with holes for entrance of the intercepted water, such that all 45 water of the spray which might make drops to be carried out of the apparatus by the air, too heavy to float, are separated from the air blast; those which are dangerous because of having in themselves too little kinetic energy 50 being collected and concentrated and dis-

charged through a zone protected from the blast in the middle of the apparatus. The conical top of the interceptor diverts air currents which are starting downward axially of the casing, from the fan, and directs them outward into the faster moving portion of the blast, which has annular form, or else, to some extent, lets this air pass with water through the funnel to the base centrally without ill effect. 55

It is intended that the patent shall cover by suitable expression in the appended claims whatever features of patentable novelty exist in the invention disclosed.

In the accompanying drawings: 60

Figure 1 is an elevation of a humidifier embodying the present invention, with the left half of the casing in medial section.

Figure 2 is an elevation of the water jet apparatus greatly enlarged showing the manner of attaching the interceptor, and 70

Figure 3 is a plan of the interceptor per se.

Referring to the drawings, and more particularly to Figure 1, a well known type of humidifier of double air current type is seen, 75 adapted to be hung from overhead by a pair of hanger straps 10 to which is attached a spider 12 supporting the motor 14 and fan 16. The usual outer and inner cylindrical casings are indicated at 18, 20 respectively, the inner 80 extending down within the outer from mid-height of the outer to a level slightly below the lower end of the outer, where, at 24, the inner casing flares abruptly outward under the outer casing.

The fan is disposed so as to draw air in at the top of the outer casing and drive it downward, some passing through the inner casing 20 and some through the annular passage *a* between the two casings. 90

The usual spray nozzle 26 is set on the axis in position for its sprayed discharge to make a conical jet downward toward the walls of the inner casing; and air from the fan above, passing down through the inner casing, entrains moisture as it goes through the spray. At the bottom this air is turned horizontally outward in all directions by the central deflector 28 which there stands up from the drip pan 22, and then is turned somewhat upward 95 100

by the flaring of the drip pan's edge 30 and is thus thrown together with the dry air currents which have come down from the fan through the annular passage *a* between the two casings. In normal operation this construction is sufficient to clear the air of all globules of entrained water which are too large to be absorbed by air in the room; but we have found trouble to arise when the jet is being stopped or started. As humidifiers of this type often operate under automatic control with frequent startings and stoppings, this condition occurs many times during a day. Such a throwing of water may be serious and may disqualify the apparatus for certain kinds of workrooms.

By the invention we provide measures to prevent large drops of the spray from reaching that region where the outgoing air has undergone its deflection from vertical to horizontal direction and is about to pass out into the atmosphere, accomplishing this prevention by a species of automatic selection, which does not affect the flow of the spray under normal pressure but only when the water jet at 26 is not operating with force sufficient to throw its spray to the walls of the inner casing 20. The selection is effected by an interceptor arranged under the spray jet and adapted by size and elevation relative to the spray to collect those of the larger spray drops which have insufficient kinetic energy to reach the casing 20. The device has a funnel 38 with an upstanding peripheral flange 40. The mouth or top of the funnel is closed by a conical air-deflecting cover 42, at whose edge is a series of openings 44 through this cover just inside the flange 40. The cover is secured within the flange in any suitable manner, and the whole is supported immediately under the impact element 46 against which the jet of water from nozzle 26 impinges for the making of the conical spray. For this support an internally threaded boss 48 on cover 42 is provided, to screw on the lower end of element 46 to a rigid position, serving also as a lock nut to maintain the impact element 46 in desired adjusted position.

The device may be made of a size with respect to the inner casing 20, and set in such position relative to the jet, that, when the jet is operating under a normal pressure, trajectory of the spray from it passes above and free of the peripheral flange 40 as for example within the conical zone indicated by the dotted lines, in which case the larger globules, which ought not to be carried out by the blast, have kinetic energy enough to pass them through the blast at this place and to drive them against the casing wall, to which they cling and from which they pass to the drain, by flow down the walls, into trough 32 and thence into the drip pan 22, shielded from air currents by suitable duct

walls 36. As soon as the jet pressure diminishes, however, or before it has attained full pressure when being started, in both of which cases the spray is less finely divided, the drooping spray and the dripping water is intercepted by the peripheral flange 40, and this water passes into the funnel through opening 44 and is guided centrally through the casing to the drip pan, shielded from the air blast. And in the intermediate stages of pressure the same is true of those of the larger drops of water which have less energy and would otherwise fall in the air blast. As a result, the danger of too large globules of water being blown from the humidifier is made practically negligible. The proper elevation and diameter of flange 40 to separate the unsafe from the safe globules thus can be determined by observation of the trajectory of the spray, depending upon the shape and character of the normal spray and its relation to the casing wall, and setting the interceptor so that it cuts the trajectory of the spray when that trajectory has fallen so that its larger drops would not reach the vertical wall of the casing but would fall into the space between it and the deflector 28. The device also serves to utilize more of the air currents for carrying moisture through the humidifier, in that the conical top of the interceptor deflects the portion of air blast at or near the axis of the casings, into the faster moving current further from the said axis where it can better aid and amplify the proper operation of the humidifier.

We claim as our invention:

1. In a forced draft humidifier having means for producing within a casing a blast of air through which water is directed in a conical jet against the wall of the casing, the combination, with a nozzle and a spraying impact element of an interceptor for the spray adapted to be attached to the said impact element in position to entrap jetted water particles, the force and direction of whose travel as deflected by said element would be insufficient to carry them to the said casing wall.

2. In a forced humidifier having means for producing within a casing a blast of air through which water is directed in a conical jet against the wall of the casing, the combination, with a nozzle, of an interceptor for the jet, comprising a funnel and deflecting cover therefor, there being openings for water to pass said cover into the funnel inside the peripheral edge of the funnel; the funnel being positioned under the said nozzle in location intercepting the trajectory of water particles jetted with less than normal operating pressure.

3. A humidifier having, in combination, a vertical casing; means for producing a blast of air downward through said casing; a spray nozzle at the axis of said casing adapt-

ed to produce a conical jet of water across
said air blast and against the casing; and
intercepting means close under said nozzle
within the hollow of said jet for deflecting
the central portion of said air blast toward
the casing and thereby creating below said
intercepting means a zone of minor air move-
ment; said intercepting means being capable
of collecting the jetted water particles whose
momentum and direction of travel would
10 prevent their reaching the casing and dis-
charging them downward through said zone.

Signed at Boston, Massachusetts, this 29th
day of September, 1926.
